Specification for Design.

Patented Apr. 10, 1917.

Application filed November 7, 1916. Serial No. 130,076. Term of patent 7 years.

To all whom it may concern:

Be it known that we, WILLIAM H. EBELHARE and CLARENCE G. ARVIDSON, citizens of the United States, residing at Indianapolis, in the county of Marion and State of Indiana, have jointly invented a new, original, and ornamental Design for a Writing-Machine Frame, of which the following is a specification, reference being had to the accompanying drawings, forming part thereof.

Figure 1 is a perspective view of a writ-

ing machine frame embodying our improved design. Fig. 2 is a plan view. Fig. 3 is a front view. Fig. 4 is a rear view, and Fig. 5 is a side view.

We claim:—

The ornamental design for a writing machine frame, as shown.

WILLIAM H. EBELHARE.
CLARENCE G. ARVIDSON.
